5 Sheets-Sheet 3

Technical drawing of a mechanical assembly, likely a press or stamping machine, showing various components and part numbers. The drawing is labeled "Fig. 6" and "Fig. 3.".

The assembly includes the following labeled parts:

- Fig. 6: 26, 25, 24, 51, 50, 55, 54, 56, 57, 49, 48, 60, 59, 62, 43, 28, 78, 23, 22, 50, 54, 39, 79, 43, 47, 26, 52, 51, 50, 55, 56, 57, 53, 58, 70, 76, 66, 69, 47, 71, 73, 79, 708, 68, 74, 701, 69, 90, 98, 95, 687, 7, 3, 2, 100, 17, 27, 22, 18, 68, 67, 101, 5, 51, 58, 57, 50, 54, 39, 21, 69, 95, 70, 107, 82, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 340, 341, 342, 343, 344, 345, 346, 347, 348, 349, 350, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385, 386, 387, 388, 389, 390, 391, 392, 393, 394, 395, 396, 397, 398, 399, 400, 401, 402, 403, 404, 405, 406, 407, 408, 409, 410, 411, 412, 413, 414, 415, 416, 417, 418, 419, 420, 421, 422, 423, 424, 425, 426, 427, 428, 429, 430, 431, 432, 433, 434, 435, 436, 437, 438, 439, 440, 441, 442, 443, 444, 445, 446, 447, 448, 449, 450, 451, 452, 453, 454, 455, 456, 457, 458, 459, 460, 461, 462, 463, 464, 465, 466, 467, 468, 469, 470, 471, 472, 473, 474, 475, 476, 477, 478, 479, 480, 481, 482, 483, 484, 485, 486, 487, 488, 489, 490, 491, 492, 493, 494, 495, 496, 497, 498, 499, 500, 501, 502, 503, 504, 505, 506, 507, 508, 509, 510, 511, 512, 513, 514, 515, 516, 517, 518, 519, 520, 521, 522, 523, 524, 525, 526, 527, 528, 529, 530, 531, 532, 533, 534, 535, 536, 537, 538, 539, 540, 541, 542, 543, 544, 545, 546, 547, 548, 549, 550, 551, 552, 553, 554, 555, 556, 557, 558, 559, 560, 561, 562, 563, 564, 565, 566, 567, 568, 569, 570, 571, 572, 573, 574, 575, 576, 577, 578, 579, 580, 581, 582, 583, 584, 585, 586, 587, 588, 589, 590, 591, 592, 593, 594, 595, 596, 597, 598, 599, 600, 601, 602, 603, 604, 605, 606, 607, 608, 609, 610, 611, 612, 613, 614, 615, 616, 617, 618, 619, 620, 621, 622, 623, 624, 625, 626, 627, 628, 629, 630, 631, 632, 633, 634, 635, 636, 637, 638, 639, 640, 641, 642, 643, 644, 645, 646, 647, 648, 649, 650, 651, 652, 653, 654, 655, 656, 657, 658, 659, 660, 661, 662, 663, 664, 665, 666, 667, 668, 669, 6610, 6611, 6612, 6613, 6614, 6615, 6616, 6617, 6618, 6619, 6620, 6621, 6622, 6623, 6624, 6625, GANG BORING MACHINE

Filed June 30, 1936

5 Sheets-Sheet 5

Technical drawing of a mechanical assembly, likely a valve or actuator, labeled 'Fig. 10.' The drawing shows a vertical assembly with various components labeled with numbers:

- Top section: A valve body with a handle (702), a seat (705), and a stem (706).
- Middle section: A piston rod (707) connected to a piston (708) with a seal (709). The piston is located in a cylinder (710) with a rod (711).
- Bottom section: A lever system with a lever arm (712) and a base (713). A spring (714) is attached to the base.
- Side components: A lever (715) and a rod (716) connected to the base.
- Other parts: A valve handle (717), a valve body (718), and a valve seat (719).

GANG-BORING MACHINE

Ose F. Carpenter, Brightwood, Va.

Application June 30, 1936, Serial No. 88,227

11 Claims. (Cl. 144—110)

This invention relates to a gang-boring machine designed primarily for boring in slats, rails or stiles, a single recess or a plurality of aligned recesses for receiving the ends of rods or dowls used in the construction of poultry coups, cribs, grilles or the like, but it is to be understood that the machine, in accordance with this invention is to be employed in any connection for which it may be found applicable.

10 One of the objects of the invention is to provide, in a manner as hereinafter set forth, a machine of the class referred to including spring controlled, slidably suspended, bodily shiftable work-feeder structures and work truing devices arranged in the path of the work carried by the feeder structures when the work is moved in the direction to be acted upon.

20 A further object of the invention is to provide, in a manner as hereinafter set forth, a machine of the class referred to with a pair of spring controlled, slidably suspended, bodily shiftable work-feeder structures and completed work dischargers arranged in the path of the work carried by said structures, when these latter move in a direction to have the work acted upon, whereby 25 the prior completed work is discharged from said structures.

30 A further object of the invention is to provide, in a manner as hereinafter set forth, a machine of the class referred to including a pair of spring controlled, slidably suspended, bodily shiftable work-feeder structures and resilient retainers for and arranged in the path of the work carried by said structures when these latter are shifted 35 in a direction to position the work to be acted upon.

40 A further object of the invention is to provide, in a manner as hereinafter set forth, a machine of the class referred to including bodily adjustable resilient work retainers when the upstanding work is being acted upon and bodily adjustable upstanding work dischargers for the completed work.

45 Further objects of the invention are to provide, in a manner as hereinafter set forth, a gang-boring machine which is simple in its construction and arrangement, strong, durable, adjustable, intermittently operating on the work at spaced points, thoroughly efficient in its use, expeditious in its action, readily assembled, conveniently repaired when occasion requires, automatically discharging the completed work, and comparatively inexpensive to manufacture.

50 With the foregoing and other objects in view, the invention consists of the novel construction,

combination and arrangement of parts as will be more specifically referred to and are as illustrated in the accompanying drawings wherein is shown an embodiment of the invention, but it is to be understood that changes, variations and 5 modifications may be resorted to which fall within the scope of the invention as claimed.

In the drawings:—

Figure 1 is an elevation looking towards one side of the machine and further illustrating the 10 work to be acted upon in dotted lines,

Figure 2 is a top plan view of the machine, broken away and further illustrating the work in full lines to be acted upon,

Figure 3 is an elevation looking towards one 15 end of the machine,

Figure 4 is a section on line 4—4, Figure 2,

Figure 5 is a sectional detail illustrating the 20 driving pulleys for the operating means for the boring tools,

Figure 6 is a fragmentary view in perspective of one end of a work-feeder structure illustrating the work guide and holder,

Figure 7 is a fragmentary view in side elevation illustrating the position of several elements 25 of the machine prior to the discharge of a completed piece of work,

Figure 8 is a view similar to Figure 7 illustrating a work discharger in position to discharge a completed piece of work as the work-feeder 30 structure is moved in a direction towards the boring tools of one set,

Figure 9 is a fragmentary view in sectional plan of a work-feeder structure relative to a 35 truing device, a retainer, and a completed work discharger,

Figure 10 is a fragmentary view in end elevation illustrating the position of non-completed work and completed work relative to a work retainer, a work truing device and a completed 40 work discharger,

Figure 11 is a lengthwise sectional view of a work truing device,

Figure 12 is a top plan view of a work truing device,

Figure 13 is a detailed section illustrating a 45 holder of the work-feeder structure with a holder arranged in relation to a piece of non-completed work and a piece of completed work,

Figure 14 is a perspective view of a piece of 50 completed work,

Figure 15 is a fragmentary view in front elevation of the machine illustrating a modified form of work truing device, and

Figure 16 is a side elevation of the form of truing device shown in Figure 15.

Referring to the drawings, the machine includes a supporting frame formed of a pair of inverted yoke-shaped members 1, 2, each of which includes a front leg 3, a rear leg 4 and a top 5. Said legs 3 and 4 are of angle-shaped sectional plan. The top 5 is of angle shape in vertical section. The legs 3, 4 have their upper ends and 10 the ends of the top 5 mitered together. The legs 3, 4 intermediate their ends are connected together by a combined brace and support 6 which is of angle contour in vertical section. Mounted on the member 6 is a bearing 7.

15 The frame includes a pair of inverted channel irons 8 and 9 which are arranged in parallel, spaced relation and extend from the top 5 of member 1 to the top 5 of member 2. The channel irons are fixedly secured to the members 1, 2.

20 The inner side of the channel iron 8 is indicated at 10 and that of the channel iron 9 at 11.

Mounted upon the channel irons 8, 9 are means to provide a pair of gear boxes 12, 13 and the said boxes have their ends spaced inwardly from 25 the ends of the channel irons 8, 9.

The box 12 includes a pair of spaced parallel side walls 14, 15, spacing strips 16, 17 seated upon the top of the walls 14, 15 respectively and a cover 18 mounted on the strips 16, 17. The 30 walls 14, 15 are of greater thickness, height and width than the strips 16, 17. The walls 14, 15 have spaced aligned openings constituting bearings. The said openings are not shown but are transversely disposed with respect to said walls.

35 The gear box 13 includes a pair of spaced parallel side walls 19, 20, spacing strips 21, 22 seated upon the top of the walls 19, 20 respectively and a cover 23 mounted on the strips 21, 22. The walls 19, 20 are of greater thickness, height and 40 width than the strips 21, 22. The walls 19, 20 have spaced aligned openings constituting bearings. The said openings are not shown but are transversely disposed with respect to the said walls. The openings in the walls 19, 20 align 45 with the openings in the walls 14, 15. The bottom of the box 12 is provided by channel iron 8. The bottom of the box 13 is provided by channel iron 9. The walls of the said boxes are suitably secured to the channel irons. The strips are 50 suitably secured to the walls. The covers are loosely mounted on the strips.

In connection with the machine there are illustrated six drive spindles 24, but this number may be increased if desired. The spindles 24 55 carry pulleys 25 operated from a drive belt 26 leading from a suitable source of power. The pulleys 25 are arranged between and spaced from the boxes 12, 13. The spindles 24 extend through aligned openings in the walls 14, 15, 19, 20 and 60 carry at one end a tool chuck 27 and at the other end a tool chuck 28. Mounted in the other openings in the walls 14, 20 and extending through the other openings in the walls 15, 19 are drive spindles provided on their outer ends with tool 65 chucks. The arrangement is clearly shown with respect to the box 12. The spindles which are journaled in one wall of a gear box and project from the other wall of a gear box are of less length than the spindles 24. The short spindles 70 are indicated at 29 and the tool chucks on the short spindles which are journaled in the walls of the box 12 are indicated at 30. The tool chucks on the short spindles which are journaled in the walls of the box 13 are indicated at 31. Each 75 spindle 24 is provided with a wide gear. The

gears are arranged within the boxes 12, 13. Each short spindle 29 is provided with a narrow gear. The short spindles are arranged in pairs. The narrow gears of a pair of short spindles mesh with the end portions of a wide gear carried by a 5 spindle 24. The wide and narrow gears in each gear box provide chains of gears as is illustrated with respect to gear box 12. The wide gears on the spindles 24 are indicated at 32 and the short gears on the spindles 29 at 33. Mounted in the tool chucks which extend from the wall 20 of box 13 are boring tools 35. Mounted in the tool chucks which extend from the wall 14 of box 12 are the boring tools 34.

The walls 14, 15, 19, 20 of the gear boxes are 15 formed with lubricant ports 36 which lead to the openings therein. The ports 36 are illustrated with respect to the walls 14, 15 of gear box 12.

The machine includes a pair of spring controlled, slidably suspended, bodily shiftable work-feeder structures. One is arranged in the front and the other at the rear of the machine. Each feeder structure alternately moves in opposite directions, but the movement of one feeder structure is alternate with respect to that of the other. 20 Both feeder structures are of the same construction and the description of one will apply to the other. The work-feeder structure at the front of the machine is indicated generally at 37 and the work-feeder structure at the back of the 30 machine is indicated generally at 38. Each feeder structure consists of a horizontally disposed oblong carrier 39 formed in proximity to each end with an opening 40 indicated in dotted lines in Figures 2, 7, and 8. Secured to the lower face 35 of the carrier and flush with the ends of the latter as well as depending therefrom are spaced parallel blocks 41 constituting a pair of combined guides and supports. Each block at its transverse center is formed with an opening 42. The 40 blocks 41 of the structure 37 align with the blocks of the structure 38. Secured to the carrier 39 is a pair of vertically extending, oppositely disposed skeleton-shaped combined guide and work directing elements 43 of like form. Each of said 45 elements 43 includes a vertically disposed member 44 of strap-like form having an out curved upper end 45, an outer vertically disposed member 46 of strap-like form, an inner vertically disposed member 47 of strap-like form provided with 50 an outwardly directed lower end terminal portion 48 (Figure 6) which is disposed at right angles to the remaining portion of member 47 and arranged below the bottom edge 49 of member 46. The member 44 is disposed at right angles to the members 46, 47. The members 46, 47 are arranged in opposed parallel spaced relation and are, further, spaced inwardly from the member 44. The lower portions of the members 44, 46 and 47 are welded or otherwise secured to a 55 horizontally disposed yoke 50. The base 51 of the latter is positioned against the outer face of the member 44. The arm 52 of yoke 50 is arranged against the outer face of the member 46. The arm 53 of the yoke 50 is positioned against 60 the rear face of the member 47. Secured against the outer face of arm 52 of yoke 50 is a coupler 54 formed with a vertical leg 55 and a horizontal leg 56. The latter extends outwardly at right angles to the bottom of the leg 55. The leg 55 65 is formed with a pair of spaced slots 57 disposed lengthwise thereof. The arm 53 of the yoke 50 of one element 43 of the pair is connected to the arm 53 of the yoke 50 of the other element 43 of the pair by an elongated bar 58 disposed on the 70 75

lower lengthwise edge thereof. The upper ends of the members 46, 47 are curved outwardly in opposite directions as indicated 59, 60. The members 44, 46 and 47 have abutting against their outer faces in proximity to their upper ends a yoke 61 which is anchored to the said members by the holdfast means 62.

The member 44 of each element 43 has its outer lengthwise edge positioned against the inner face of the carrier 39 adjacent one end of the latter. The member 46 of each element 43 has its outer face positioned against the inner side of the carrier 40. The couplers 54 of the element 43 have their legs 56 positioned upon the top face of the carrier 39 adjacent the ends of the latter. The members 47 of the elements 43 depend below the carrier 39. The legs 56 of the couplers 55 of the elements 43 are secured to the carrier 39 by the holdfast means 63 which detachably engage in the carrier 39. The holdfast means 63 in connection with the slots 57 in the legs 56 provide for the adjusting of one of the elements 43 towards and from the other. It will be stated that one of the elements 43 may be permanently fixed 25 to the carrier 39 and the other element 43 may be adjustably connected to the carrier 39. The work to be operated upon will be of strip-like form and is mounted in superimposed relation in the pair of elements 43 in a manner as indicated by the dotted lines showing 64 (Figure 1). The curved upper ends of the members 44, 46 and 47 of the elements 43 facilitate the entrance of the work into a work-feeder structure. The lower end terminal portions 48 of the members 35 47 of a pair of elements 43 are arranged in parallel spaced alignment and such portions 48 constitute supports for the completed work, indicated at A and in this connection attention is directed to Figures 7 and 8. The incomplete work, next 40 above the completed work A is indicated at B. Adjustably secured to the bar 58 and depending therefrom are L-shaped members 65 functioning for the same purpose as the angle-shaped lower end terminal portions 48 of the members 47 of a 45 pair of elements 43.

The machine includes a pair of suspension bars 66 which are common to the work feeder structures 37, 38. The bars are disposed transversely of the channel members 8, 9 and extend 50 forwardly with respect to the front and rearwardly with respect to the back of the machine. The bars 66 are anchored to the inner edges of the channel members 8, 9 as at 67 and to the outer edges of the channel members 8, 9 at 68. 55 The anchoring means 68 are spaced from the anchoring means 67. The anchoring means 68 constitute abutments and are flush with the outer side edges of the channel members 8, 9. The bars 66 extend through the openings 42 in the 60 blocks 41 of the structures 37, 38 and normally have their outer end terminal portions extended beyond the work-feeder structures. Interposed between the several anchoring means 68 and the rear edges of the several blocks 41 and encompassing the bars 66 are controlling springs 69 normally functioning to maintain the work-feeder structures 37, 38 in outwardly extended 65 relation with respect to the boring tools 34, 35.

The work-feeder structures 37, 38 are shifted 70 in a direction to position the work to be acted upon and against the action of the springs 69 by similar actuatable shifting mechanisms 70, 71 respectively arranged in pairs. Each of said shifting mechanisms includes an upstanding lever arm 72 pivotally connected intermediate its

ends as at 73 to a bracket 74 connected to a fixed hanger 75 (Figures 1 and 4). The upper end of the lever 72 is provided with an eye 76 into which extends the angle-shaped inner end 77 of a threaded pull member 78 extending 5 through an opening 40 in a carrier and adjustably connected to the latter by the nuts 79. The pull members 78 are spaced outwardly with respect to the elements 43 of the structure 37, 38. The levers 72 of the shifting mechanisms 70, 71 10 move in a rearward direction together and in a forward direction together. When the levers 72 of the mechanisms 70 move rearwardly and the levers 72 of mechanisms 71 are moved forwardly, that is to say, the upper ends of said levers, 15 the work-feeder structures 37, 38 are pulled in a direction to position the work to be acted upon, and when the upper ends of the levers 72 of the mechanism 70 are moved forwardly and the upper ends of the levers 72 of mechanism 20 71 moved rearwardly, the work-feeder structures are shifted in a direction away from the boring tools and which action is assisted by the controlling springs 69 which are associated with the carriers of the work-feeder structures. 25

An actuating mechanism (see Fig. 4) is provided for the shifting mechanism 70 and said actuating mechanism consists of a pair of actuating bars 80 which are adjustably connected at their outer ends, as at 81 to the lower ends of the 30 levers 72 of the mechanism 70. The levers 72 of the mechanism 70 are simultaneously operated by the bars 80 in like directions. The bars 80 at their inner ends are provided with rollers 82. The bars 80 have their inner terminal portions 35 suspended by upstanding suspenders 83 which are pivotally connected at their upper ends, as at 84 to lugs 85 carried by the inner side 10 of the channel iron 8. The lower ends of the suspenders 83 are pivotally connected as at 86 to 40 the bars 80.

An actuating mechanism is provided for the shifting mechanism 71 and such actuating mechanism consists of a pair of actuating bars 87 which are adjustably connected at their outer 45 ends, as at 88 to the lower ends of the levers 72 of the mechanism 71. The levers 72 of the mechanism 71 are simultaneously operated by the bars 87 in like directions. The bars 87 at their inner ends are provided with rollers 89. 50 The bars 87 have their inner end terminal portions suspended by upstanding suspenders 90 which are pivotally connected at their upper ends, as at 91 to lugs 92 carried by the inner side 11 of channel iron 9. The lower ends of the 55 suspenders 90 are pivotally connected as at 93 to the bars 87.

The actuating mechanisms for the shifting mechanisms 70, 71 are operated from a pair of cams 94 mounted in spaced relation on a cam 60 shaft 95. Cams 94 are of like contour. The cams 94 are arranged between the rollers 82 of the said actuating mechanisms. The cams 94 are so shaped that when acting on the rollers 82, 89 they will move the actuating bars 80 in 65 a forward direction when the bars 87 are moved in like direction, or in other words cams 94 provide for alternately shifting the bars 80 forwardly and the bars 87 rearwardly, under such conditions providing for the alternate shifting 70 of the work-feeder structures in opposite directions. Cam shaft 95 is provided with a worm gear 96 driven from a worm 97 fixed to a rotatable shaft 98 carrying a pulley 99 operated from an endless belt 100 driven from a prime mover 75

not shown, and mounted in bearing means indicated at 101.

There is associated with each work-feeder structure a pair of resilient work retainers acting 5 to maintain the work stationary as the latter is being moved to be acted upon and when acted upon. The retainers which are associated with the work-feeder structure 37 are indicated at 102 and are arranged in spaced relation. The retainers which are associated with the work-feeder structure 38 are indicated at 103. The work retainers are of like form and each consists of an upstanding resilient strap 104 formed with a rearwardly directed part 105 merging into an outwardly directed tapered part 106 for bearing against the work to be acted upon as the work is fed to the tool (Figure 7).

There is associated with each work-feeder structure a pair of completed work dischargers. 20 The dischargers which are associated with the work-feeder structure 37 are indicated at 107. The pair of completed work dischargers which are associated with the work-feeder structure 38 are indicated at 108. Each of the completed work 25 dischargers is of the same construction and consists of an upstanding tapered arm 109 formed at its upper end with a laterally extended and outwardly directed nose 110 (Figure 8) providing an abutment for the completed work and acting 30 to discharge the completed work from a work-feeder as the latter moves in the direction to position a piece of work to be acted upon.

There is common to the retainers 102 and dischargers 107 a tensioned supporting means 111 therefor. There is common to the retainers 103 and the dischargers 108 a tensioned supporting means 112 therefor. The tensioned supporting means 111, 112 are of like form and each consists 35 of a pair of bearing brackets 113, a shaft 114 mounted in the brackets 113, spaced keys 115 on shaft 114, a spring controlled crank arm 116 having a hub 117 fixed to shaft 114 in proximity to one of the brackets 113 and a laterally disposed apertured ear 118 to which is connected a fixed 40 bolt 119 carrying an adjustable tensioning spring 120 which is interposed between the ear 118 and member 1. Each discharger 107 has a hub 121. The latter is keyed on shaft 114 as well as being held stationary on the shaft by a binding screw 122. The shaft 114 has keyed thereon a pair of 45 spaced blocks 123 and each of which is fixed to shaft 114 by a binding screw 124. The outer face of each block is anchored as at 125 to the lower end 126 of a retainer. Each shaft 114 will 50 carry a pair of retainers and a pair of dischargers. The retainers will be arranged in spaced relation on the shaft 114 and between and in spaced relation to the pair of dischargers fixed to the shaft 114.

60 The brackets 113 of the tensioned supporting means for the retainers and dischargers which associate with the work-feeder structure 37 are secured to the front of the legs 3 of the members 1, 2. The brackets 113 of the tensioned supporting means 112 for the retainers and dischargers which associate with the work-feeder structure 38 are anchored to the legs 4 of the members 1, 2. The bolt 119 of the tensioned supporting means 111 is secured to the leg 3 of the member 1. The bolt 119 of the tensioned supporting means 112 is secured to the leg 4 of the member 1.

There is associated with the work-feeder structure 37 a pair of spaced work truing devices 75 and with the work-feeder structure 38 a pair of

spaced work truing devices. The said work truing devices are of the same form and are adjustable and the description of one will apply to the other. The work truing devices which are associated with the work-feeder structure 37 are secured to the outer side of the channel member 8 and extend outwardly therefrom. The work truing devices which are associated with the work-feeder structure 38 are secured to the outer side of the channel member 9 and extend outwardly 10 therefrom. The form of each of the work truing devices is more clearly shown in Figures 10, 11, and 12. Each of the work truing devices is indicated at 127 and consists of a rear horizontally disposed angle-shaped member 128 formed 15 with a depending flange 129 which is secured to a channel member by the holdfast means 130. An angle-shaped member 131 is seated on the member 128 and has its flange 132 oppositely disposed with respect to the flange 129. Flanges 20 129 and 132 extend vertically. The member 131 has a slot 133. Member 131 is connected to the member 128 by the holdfast means 134. The means 134 in connection with the slot 133 provides for the adjusting of the member 131 relative to 25 member 128. Abutting against the flange 132 is a vertically disposed work truing member 135 formed with a vertical stretch 136, a horizontally disposed stretch 137 and a stretch 138 which depends from the outer end of the stretch 137 30 and is disposed in parallel spaced relation to the stretch 136. The latter is of greater length than the stretch 138. The point of emergence of the stretch 137 with stretch 138 is rounded or beveled as indicated at 139. The top of stretch 137 provides 35 a seat 140 for the piece of work to be acted upon.

The stretch 136 has a slot 141. The stretch 136 is connected to the flange 132 by the holdfast means 142 which extends through the slot 40 141. The latter in connection with the holdfast means 142 provides for the vertically adjusting of the member 135 relative to the flange 132. The device 127 functions to elevate the work to be acted upon for truing the latter as it is 45 being moved in the direction to be acted upon. The rounded point of emergence between stretches 137 and 138 facilitates the elevating of the work when truing the same. The truing devices are stationary and when positioned the 50 stretches 138 thereof also act to assist in the discharging of the completed work.

A strap or bar which has been acted upon is indicated at 143 (Figure 14).

The elements 43 of each work-feeder structure 55 in connection with their connecting bar 58 and the member 65 provide a magazine in which the work, i. e. slats, rails or stiles are supported therein in superimposed stack-relation as the work-feeder structure moves towards and from 60 a set of boring tools. The magazine has its lower portion of its front open.

The work in the magazine moves to a position to be subsequently acted upon by gravity after a completed piece of work A has been discharged 65 therefrom. The work to be acted upon is that piece B which is supported upon a completed piece A at the bottom of the stack. As the piece B to be acted upon is moved towards the set of boring tools, the completed piece A is automatically discharged, but during the discharge the truing devices act to support the next piece B which is to be acted upon and after completion of the said next piece, it is supported by the truing devices until the work-feeder structure clears 70 75 75

the truing devices which permits the said next completed piece of work A to fall by gravity to the bottom of the magazine thereby providing for another piece of work B to move downwardly 5 to a position to be acted upon. As the work-feeder structure 37 moves towards a set of boring tools to complete a piece of work B and a completed piece of work A is discharged from its magazine, the work-feeder structure 38 moves 10 away from a set of boring tools to provide for a completed piece of work A to fall to the bottom of its magazine and a non-completed piece of work B to be arranged in superimposed relation with the said completed piece of work A, 15 whereby when structure 38 moves towards the set of boring tools, the action upon the two pieces of work will be the same as that referred to in connection with the structure 37 when the latter moves towards a set of boring tools. 20 The work to be acted upon is manually supplied, at the upper ends of the elements 43, of each work-feeder structure as the stacks of work carried by said structures lower due to the discharge of the completed pieces of work from the 25 magazines.

With reference to Figures 15 and 16, a modified form of work truing device is indicated at 144. The work truing devices 127 as heretofore referred to are secured to the channel members 8, 30 9, whereas the devices 144 are keyed to and adjustable lengthwise of the shaft 114. Preferably a pair of truing devices 144 will be mounted on a shaft 114. Each device 144 will consist of an arm 145 formed at its lower end with a collar 35 or hub 146 which is slidably keyed on shaft 114. The hub 146 carries a binding screw 147 for securing arm 145 in its adjusted position on shaft 114. The arm 145 has a laterally extended offset upper terminal portion 148 formed with an 40 opening 149. Positioned against one side face of portion 148 is a rectangular plate constituting a seat forming member 150 formed in proximity to and parallel with one of its lengthwise edges a slot 151 which is intersected between its transverse median and its inner end by the vertical median of said member. The latter is horizontally and vertically adjustable relative to the offset portion 148 of arm 145. The member 150 is fixedly secured in its adjusted position by a bolt 45 152 which extends through opening 149 and slot 151 and carries a clamping nut 153.

The slot 151 is arranged in the member 150 at the position shown to provide for greater range of adjustment by reversing the member 150 or turning the bottom edge up. The member 150 50 as before stated is of rectangular contour, has rounded corners and is faced on all four edges so that either one of these latter may be placed up to serve as the seat for the work to be acted upon. The device 144 preferably is to be arranged on shaft 114 between a work discharger and a work retainer. So far as functioning is concerned, the truing device 144 functions the same as the truing device 127, with the additional 55 advantages of being placed at any point along the work to be trued, either at the end or near the center of the work, and further that it may be pushed out of the way without any damage in case the work becomes jammed against it.

With respect to the operation of the machine, 60 it will be said the work-feeder structures 37, 38 alternately shift in opposite directions, that is to say, when one work-feeder structure moves towards one gang of boring tools, the other work-feeder structure moves away from the other gang 65

of boring tools. The action of the machine upon the work carried by the feeder structure 37 will be described, as such description will apply to the work carried by the other feeder structure 38.

The work is arranged in superimposed relation 5 in a stack-like manner within the work-feeder structure. A completed piece of work A is discharged from the bottom of the feeder structure 37 which lowers the stack and another piece of work B is then mounted on the top of the stack. 10 The completed piece of work A is at the bottom of the stack and it is discharged while the incompletely piece of work B next above the completed piece of work A moves downward and is supported by the supports 65 in a position to be 15 operated on by the tools of a gang.

It will be assumed that a piece of work has been acted upon and that it is the lowermost piece of work A of the stack in the feeder structure 37 and that the latter is in its outermost 20 position, such as shown in Figure 7. The two lowermost pieces of work A, B of the stack appearing as shown in Figures 7, 8, 10, 11, and 13. As the work-feeder structure 37 moves inwardly, it disposes the next to the lowermost piece A of 25 the stack in a position to be acted upon by the boring tools of the gang. As the work-feeder structure 37 moves inwardly, the lowermost piece of work A will abut the dischargers 107 and on continual inward movement of the feeder structure 37, the discharger 107 will provide for the completed piece of work A at the bottom of the stack to be discharged from the work-feeder structure 37. However, the discharge of the completed work A will not take place until the piece 30 of work B which is to be operated on is trued and supported by the truing devices 127 or 144. As the work-feeder structure 37 moves inwardly before the completed work A is discharged, the completed piece of work A and the piece of work 35 B to be operated on come in contact with the truing devices 127 or 144 whereby the work B to be acted on is trued by and supported upon the truing devices which in turn support the pieces of work arranged thereover within the 40 work-feeder structure 37. When the piece of work B which is to be operated upon is supported by the truing devices 127 or 144, it is arranged in the work-feeder structure 37. The latter moves a sufficient distance inwardly to 45 provide for a gang of boring tools acting on the piece of work B supported by the truing devices 127 or 144. When the work-feeder structure 37 moves inwardly to have the next to the lowermost piece of work B of the stack to be acted 50 upon, the said piece of work B abuts the resilient elements 102 whereby such piece of work B will be held stationary in the work-feeder structure 37, as it is being acted upon. When the piece of work B to be acted upon is supported by the truing devices 127 or 144, the completed piece of 55 work A is discharged whereby that portion of the work-feeder structure 37 below the piece of work being acted upon is vacant and with the work to be acted upon being arranged within the feeder structure 37 and supported by the truing devices 127 or 144. As the work-feeder structure 37 moves outwardly, the completed piece of work 60 A which is on the truing devices 127 or 144 is carried off or cleared the truing devices 127 or 144 at which time the stack in the work-feeder structure 37 will lower therein making the completed piece of work A the lowermost piece of the stack and arranging the next upper piece of work B in position to be acted upon.

What I claim is:—

1. In a gang-boring machine, a slidably mounted work-feeder structure having means for slidably supporting the work to be acted upon in superimposed stack-like relation, means for shifting said structure in an inward direction to dispose the next to the lowermost piece of work of the stack in a position to be acted upon by boring tools, means arranged in the path of said structure, when the latter moves inwardly for discharging the lowermost piece of work from said structure to provide for the other piece of work, after being acted upon, to constitute the bottom piece of work of the stack when said structure is moved outwardly, means arranged in the path of said structure, when the latter moves inwardly for truing the said piece of work to be acted upon and constituting a support for the latter during the discharge of the said lowermost piece of work, and said means for shifting said structure inwardly providing for the shifting of said structure outwardly on the completion of the said other piece of work.
2. In a gang-boring machine, a slidably mounted work-feeder structure having means for slidably supporting the work to be acted upon in superimposed stack-like relation, means for shifting said structure in an inward direction to dispose the next to the lowermost piece of work of the stack in a position to be acted upon by boring tools, means arranged in the path of said structure, when the latter moves inwardly for discharging the lowermost piece of work from said structure to provide for the other piece of work, after being acted upon, to constitute the bottom piece of work of the stack when said structure is moved outwardly, means arranged in the path of said structure, when the latter moves inwardly for truing the said piece of work to be acted upon and constituting a support for the latter during the discharge of the said lowermost piece of work, and said means for shifting said structure inwardly providing for the shifting of said structure outwardly on the completion of the said other piece of work, and resilient means arranged in the path of said structure, when the latter moves inwardly for retaining the said other piece of work stationary while the latter is being acted upon.
3. In a gang-boring machine, a slidably mounted work-feeder structure having means for slidably supporting the work to be acted upon in superimposed stack-like relation, means for shifting said structure in an inward direction to dispose, the next to the lowermost piece of work of the stack, in a position to be acted upon by boring tools, a pair of upstanding completed work dischargers arranged in the path of said structure, when the latter moves inwardly for discharging the lowermost piece of work from said structure to provide for the said other piece of work, after being acted upon, to constitute the bottom piece of work of the stack when said structure is moved outwardly, spaced truing devices arranged in the path of said structure, when the latter moves inwardly for truing the said piece of work to be acted upon and providing supports for the latter during the discharge of the said lowermost piece of work, said means for shifting said structure inwardly providing for the shifting of said structure outwardly on the completion of the said other piece of work, and upstanding spaced resilient retainers arranged in the path of said structure, when the latter moves inwardly for retaining the said other piece of work.
4. In a gang-boring machine, a slidably mounted work-feeder structure having means for slidably supporting the work to be acted upon in superimposed stack-like relation, means for shifting said structure in an inward direction to dispose, the next to the lowermost piece of work of the stack, in a position to be acted upon by boring tools, a pair of upstanding completed work dischargers arranged in the path of said structure, when the latter moves inwardly for discharging the lowermost piece of work from said structure to provide for the said other piece of work, after being acted upon, to constitute the bottom piece of work of the stack when said structure is moved outwardly, spaced truing devices arranged in the path of said structure, when the latter moves inwardly for truing the said piece of work to be acted upon and providing supports for the latter during the discharge of the said lowermost piece of work, said means for shifting said structure inwardly providing for the shifting of said structure outwardly on the completion of the said other piece of work, upstanding spaced resilient retainers arranged in the path of said structure, when the latter moves inwardly for retaining the said other piece of work stationary while the latter is being acted upon, and a tensioned support common to said dischargers, devices and retainers.
5. In a gang-boring machine, a slidably mounted spring controlled work-feeder structure having an upstanding skeleton magazine for slidably supporting the work to be acted upon in superimposed stack-like relation, said magazine being open at the lower portion of its front, means for shifting said structure in an inward direction to dispose, the next to the lowermost piece of work of the stack, in a position to be acted upon by boring tools, a plurality of upstanding completed work dischargers arranged in the path of said structure, when the latter moves inwardly, for discharging the lowermost piece of work from the lower portion of said magazine in an outward direction to provide for the said other piece of work, after being acted upon, to constitute the bottom piece of work of the stack when said structure moves outwardly, said means for shifting said structure inwardly providing for the shifting of said structure outwardly on the completion of the said other piece of work, combined truing and supporting devices for the piece of work to be acted upon arranged in the inward path of said structure, a plurality of resilient retainers for the piece of work to be acted upon arranged in the inward path of said structure, and a tensioned supporting means common to said dischargers, devices and retainers.
6. In a gang-boring machine, an oppositely horizontally shiftable slidably supported work-feeder and carrier structure having means for carrying pieces of work to be acted upon in superimposed relation and for successively positioning the pieces of work to be acted upon, a pair of vertically and horizontally adjustable combined work truing and supporting devices for the successively positioned pieces of work to be acted upon disposed within the paths of and free of connection to movement of said structure, and means for alternately shifting said structure horizontally in opposite directions.
7. In a gang-boring machine, an oppositely horizontally shiftable, spring controlled, slidably suspended vertically disposed work-feeder struc-

ture for positioning work to be acted upon, up-
standing completed work dischargers active in
the path of one direction of movement of said
structure for abutting completed work to dis-
charge it from the bottom of said structure on
the horizontal movement of the latter in a direc-
tion to position another piece of work to be act-
ed upon, and means for horizontally shifting
said structure alternately in opposite directions.
10 8. In a gang-boring machine, an oppositely
shiftable work-feeder structure for carrying
work to a position to be acted upon by boring
tools and for carrying completed work from said
tools, means disposed in the path of movement
15 of said structure for abutting completed work
to discharge it from said structure as the latter
shifts in a direction to position work to be acted
upon, means for shifting said structure in oppo-
site directions, work retainers arranged in the
20 path of movement of said structure for bearing
on the work being acted upon as said structure
shifts in a direction to position work to be acted
upon, and combined work truing and supporting
devices for the work to be acted upon as said
25 structure shifts in a direction to position work
to be acted upon.

9. In a gang-boring machine, an oppositely
shiftable work-feeder structure for carrying work
to be acted upon in superimposed relation and
30 work to be acted upon in superimposed relation
with respect to completed work, means in the

path of said structure for discharging a prior
completed piece of work from said structure to
provide for a subsequent completed piece of work
to assume the position of the discharged piece
of work, and means arranged in the path of said
5 structure for truing and holding a piece of work
to be acted upon during the discharge of a com-
pleted piece of work.

10. In a gang-boring machine, an oppositely
shiftable work-feeder structure for carrying work
10 to be acted upon in superimposed relation and
work to be acted upon in superimposed relation
with respect to completed work, means in the
path of said structure for discharging a prior
completed piece of work from said structure to 15
provide for a subsequent completed piece of work
to assume the position of the discharged piece
of work, means arranged in the path of said
structure for retaining a piece of work station-
ary while the latter is being acted upon, and 20
means arranged in the path of said structure for
truing and holding said piece of work being
acted upon during the discharge of a completed
piece of work.

11. The invention as set forth in claim 10 hav- 25
ing combined therewith a tensioned support com-
mon to the completed work discharge means, the
work retaining means and the work truing and
holding means, said several means being ad-
justably secured to said support. 30

OSE F. CARPENTER.
